US00D962371S

(12) **United States Design Patent** (10) Patent No.: **US D962,371 S**
Parsons et al. (45) Date of Patent: **** Aug. 30, 2022**

(54) **GOLF CLUB HEAD**

(71) Applicant: **PARSONS XTREME GOLF, LLC**,
Scottsdale, AZ (US)

(72) Inventors: **Robert R. Parsons**, Scottsdale, AZ
(US); **Michael R. Nicolette**, Scottsdale,
AZ (US); **Bradley D. Schweigert**, Cave
Creek, AZ (US)

(73) Assignee: **PARSONS XTREME GOLF, LLC**,
Scottsdale, AZ (US)

(**) Term: **15 Years**

(21) Appl. No.: **29/829,154**

(22) Filed: **Mar. 3, 2022**

Related U.S. Application Data

(63) Continuation-in-part of application No. 29/812,322, filed on Oct. 20, 2021, which is a continuation of application No. 29/787,023, filed on Jun. 3, 2021, now Pat. No. Des. 935,542, which is a continuation-in-part of application No. 29/767,421, filed on Jan. 22, 2021, now Pat. No. Des. 922,506, which is a continuation-in-part of application No. 29/745,151, filed on Aug. 4, 2020, now Pat. No. Des. 916,220.

CLAIM

The ornamental design for a golf club head, as shown and described.

DESCRIPTION

FIG. 1 is a top perspective view of a golf club head according to a first embodiment;

FIG. 2 is a bottom perspective view of the golf club head of FIG. 1;

FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view of the golf club head of FIG. 1;
FIG. 7 is a left side view of the golf club head of FIG. 1;
FIG. 8 is a right side view of the golf club head of FIG. 1;
FIG. 9 is a top perspective view of a golf club head according to a second embodiment;
FIG. 10 is a bottom perspective view of the golf club head of FIG. 9;
FIG. 11 is a front elevational view of the golf club head of FIG. 9;
FIG. 12 is a rear elevational view of the golf club head of FIG. 9;
FIG. 13 is a top view of the golf club head of FIG. 9;
FIG. 14 is a bottom view of the golf club head of FIG. 9;
FIG. 15 is a left side view of the golf club head of FIG. 9;

FIG. 16 is a right side view of the golf club head of FIG. 9;
FIG. 17 is a top perspective view of a golf club head according to a third embodiment;
FIG. 18 is a bottom perspective view of the golf club head of FIG. 17;
FIG. 19 is a front elevational view of the golf club head of FIG. 17;
FIG. 20 is a rear elevational view of the golf club head of FIG. 17;
FIG. 21 is a top view of the golf club head of FIG. 17;
FIG. 22 is a bottom view of the golf club head of FIG. 17;
FIG. 23 is a left side view of the golf club head of FIG. 17;
and,
FIG. 24 is a right side view of the golf club head of FIG. 17.
The broken lines shown on the drawings form no part of the claimed design. Portions of the golf club head are stippled heavier and lighter to illustrate contrasting surfaces of different color.
